SENECA L. BERRY, OF SUNNYVALE, CALIFORNIA, ASSIGNOR TO LEON ST. D. ROYLANCE
AND FRANK H. SEARLS, BOTH OF SAN FRANCISCO, CALIFORNIA.

AGITATOR.

1,249,002.

Specification of Letters Patent.

Patented Dec. 4, 1917.

Application filed July 12, 1916. Serial No. 108,851.

To all whom it may concern:

Be it known that I, SENECA L. BERRY, a citizen of the United States, and a resident of Sunnyvale, Santa Clara county, State of California, have invented a certain new and useful Agitator, of which the following is a specification.

The invention relates to agitators for carrying out metallurgical operations and 10 particularly to amalgamating agitators.

An object of the invention is to provide a self-contained agitator.

Another object of the invention is to provide an agitator amalgamator in which the 15 pulp is brought into gentle recurrent contact with the mercury.

Another object of the invention is to provide a mechanically driven hydraulic agitator in which the jets issue from the agitator 20 in the direction of its rotation.

The invention possesses other advantageous features, some of which, with the foregoing, will be set forth at length in the following description where I shall outline in 25 full that form of the invention which I have selected for illustration in the drawings accompanying and forming part of the present specification. In said drawings I have shown only one specific form of my generic 30 invention, but it is to be understood that I do not limit myself to such form, since the invention may be embodied in a multiplicity of forms, each constituting a species of my invention.

35 Referring to said drawings:

Figure 1 is a vertical section through a tank or vessel containing the agitating apparatus of my invention.

Fig. 2 is a section taken on the line 2—2, 40 Fig. 1.

Fig. 3 is a detail of the tank discharge control.

Fig. 4 is a vertical section of the clean-up outlet for the tank.

45 Fig. 5 is a vertical section of the circulating pump which is arranged within the tank.

Fig. 6 is a section taken on the line 5—5, Fig. 5.

50 Fig. 7 is a detail of the bearing for the worm shaft which drives the agitator.

The agitator of my invention is used preferably in the treatment of valuable metal bearing ores and is particularly adapted to 55 be used as an amalgamator. The apparatus

comprises a tank 2, preferably formed with an iron bottom 3 upon which a suitable quantity of mercury is placed. Heretofore, as far as I am aware, in agitating amalgamators employing a hydraulic agitator for 60 agitating the pulp and bringing it into recurrent contact with the mercury, the agitator has been rotated by the reaction of the jets discharging therefrom. This construction has certain deleterious features which 65 are overcome by the present apparatus. In the prior devices, the force of the issuing jets agitated the mercury, causing it to flour and consequently producing a loss of amalgam. Also in the former devices the direction of rotation of the agitator is contrary 70 to the direction of discharge of the jets and on this account the jets must be forceful in order to drive the metallic particles against the mercury. In accordance with my invention, I drive the agitator mechanically so that 75 much more gentle discharge jets may be used and these jets are preferably discharged in the direction of rotation of the agitator, so that the particles of metal are 80 directed against the mercury, but the agitator may be rotated in the opposite direction when desired.

Arranged centrally within the tank 2 and rotatably mounted on the bearing ring 4, 85 which is attached to the cross beam 5, is a pump casing 6 arranged to be entirely submerged by the pulp in the tank. The casing 6 is secured to a hollow neck 7 which extends upward into contact with the bearing ring. Secured to the neck 7 above the level of the liquid in the tank is a worm wheel 8 which is engaged by a worm secured 90 to shaft 9, rotation of the shaft serving to rotate the pump case. The shaft 9 at its inner end adjacent the worm is mounted in a bearing 12 which is eccentrically mounted in the block 13, so that, should the rotation of the pump chamber be resisted to a point where undue strains are placed thereon, the 100 reaction of the worm will cause the bearing to move in the block 13 and allow the worm to disengage the worm wheel.

The pump casing is annular in shape and is provided with a flaring mouth 14 at the 105 top to permit the ready inflow of pulp and is provided with guide vanes 30 which arrest the rotation of the pulp. Within the casing is a horizontally disposed turbine impeller 15 having vanes 20 which is secured 110

to the shaft 16 extending vertically through the neck 7, and which is suitably supported therein. Rotation of the impeller serves to draw the pulp into the casing and force it 5 into the diffusion chamber 17 forming the lower part of the casing. Secured to the lower part of the diffusion chamber and in communication with the interior thereof, are a plurality of hollow arms 18, provided on 10 their forward faces with a plurality of spaced apertures 19, preferably consisting of slots cut through the walls of the arms in such manner that the streams of pulp discharging therefrom are inclined toward 15 the surface of the mercury. The arms 18 are preferably off-set slightly from a radial position, so that the issuing jets strike the mercury along a substantially radial line, thereby obviating the tendency of the jets 20 to force the heavier material toward the periphery of the tank, a condition which obtains when the arms are radially disposed.

Means are provided for indicating when 25 the arms or apertures therein become clogged and for removing the cause of the clogging. Supported upon the neck 7 and rotatable therewith, is a casing 21 in which is arranged a pressure gage 22. The casing 21, in which air is entrapped, is connected 30 to the chamber 17 and indicates the pressure in the chamber. The air entrapped in the casing 21 prevents the pulp or liquid from coming into contact with the operating parts of the gage. Under normal conditions of 35 operation, the pressure at the gage remains substantially constant, but should the apertures become clogged, the pressure gage will indicate that condition.

The impeller shaft 16 is rotated from the 40 shaft 23 which is driven directly by an electric motor or by a belt from a counter-shaft. By reversing the direction of rotation of the impeller, for a brief period, the material clogging the apertures is dislodged. When 45 an electric motor is employed to drive the impeller, the motor may be reversed, and when a belt drive is employed, a reversing gear is preferably used. In the present construction I have employed a reversing gear, 50 comprising the friction cones 24 and 25 secured to shaft 16 and a drive friction cone 26 secured to shaft 23. The shaft 23 is provided on its inner end with an eccentric bearing mounting 27 which is rotated by the 55 handle 28 to move the drive friction into contact with either of the frictions 24 or 25, thereby reversing the direction of rotation of the impeller. The shaft 9, which drives the pump casing, is preferably driven 60 from the shaft 23, through the cone pulleys 31 and 32 and the belt 33, a construction which permits the speed of the agitator to be varied with relation to the speed of the impeller.

65 The pulp to be treated flows into the tank

through the pipe 34 which extends into the tank a sufficient distance so that the entering material is caught by the pump suction and projected against the mercury. This insures that the particles of metal are 70 brought at least once into impinging contact with the mercury, and the recirculation of the pulp through the pump, insures the bringing of the particles into recurrent impinging contact with the mercury. The 75 pulp discharges from the tank through the pipe 35, preferably into a similar apparatus where the agitating and amalgamating action is continued, and the flow of pulp into and out of the tank is preferably continuous. 80 The pipe 35 is provided on its inner end with a movable inlet 36, which permits the discharging liquid to be drawn from the desired level in the tank. The position of the inlet is adjusted by the handle 37 and by 85 moving the handle, the height of the inlet opening is varied so that lighter or heavier pulp particles may be withdrawn.

The tank is preferably mounted on three 90 points of support, two of the supports 41 being shown in Fig. 1, so that the tank may be readily leveled to obtain an even distribution of the mercury over the bottom thereof. The tank is provided in the bottom with a clean-up outlet 42, through which 95 the mercury is discharged. This outlet is normally closed by a plug 43 mounted on the stem 44, the outlet being so formed that it lies flush with the bottom of the tank.

I claim:

1. An apparatus of the character described, comprising a tank, a hollow armed rotatable structure arranged in said tank adjacent the bottom thereof and a pump arranged within said structure and adapted 105 to force liquid through said arms and toward said bottom.

2. An apparatus of the character described, comprising a tank, a casing rotatably mounted in said tank, hollow arms extending outwardly from said casing and a rotatable impeller in said casing adapted to force liquid through said arms and means for rotating the impeller independently of the casing.

3. An apparatus of the character described, comprising a tank, a casing rotatably mounted in said tank, hollow arms extending outwardly from said casing and a rotatable impeller in said casing adapted to 120 force liquid through said arms and means for mechanically rotating said casing.

4. An apparatus of the character described, comprising a tank adapted to contain liquid, an open casing rotatably supported in said tank and submerged in the liquid therein, hollow arms extending outwardly from said casing and a rotatable impeller in said casing adapted to force liquid through said arms.

5. An apparatus of the character described, comprising a tank adapted to contain liquid, an open casing rotatably supported in said tank and submerged in the liquid therein, hollow arms extending outwardly from said casing and a rotatable impeller in said casing adapted to force liquid through said arms and means for reversing the direction of rotation of said impeller with respect to said casing whereby the direction of flow of liquid through the arms is reversed.
6. An apparatus of the character described, comprising a tank adapted to contain liquid, an open casing rotatably supported in said tank and submerged in the liquid therein, hollow arms extending outwardly from said casing and a rotatable impeller in said casing adapted to force liquid through said arms and means for reversing the direction of rotation of said impeller and means for mechanically rotating said casing.
7. An apparatus of the character described, comprising a tank adapted to contain liquid, a rotatable pump casing arranged centrally in said tank and submerged in the liquid therein and adapted to receive liquid directly from the liquid in the tank, a plurality of hollow arms extending outwardly from said casing and an impeller in said casing.
8. An apparatus of the character de-
- scribed, comprising a tank, a rotatable pump casing arranged in said tank, a plurality of hollow arms extending outwardly from said casing, an impeller in said casing, means for rotating the impeller, means for rotating the casing and means for varying the speed of the casing with relation to the speed of the impeller.
9. In an apparatus of the character described, a tank, a pump casing rotatable about a vertical axis arranged in said tank, said casing being provided with a flaring inlet mouth, a rotatable impeller in said casing, having a different angular velocity than said casing and hollow apertured arms extending outwardly from said casing.
10. In an apparatus of the character described, a tank adapted to contain liquid, a rotatable pump casing arranged in said tank, a rotatable impeller arranged in said casing, hollow apertured arms extending from said casing, means for indicating the pressure in said casing and means for reversing the direction of rotation of the impeller.

In testimony whereof, I have hereunto set my hand at Winnemucca, Humboldt county, Nevada, this 1st day of July 1916.

SENECA L. BERRY.
